CLAIM

The ornamental design for a safety waistband, as shown and described.

DESCRIPTION

FIG. 1 is a perspective view of a safety waistband showing my new design;

FIG. 2 is an enlarged bottom plan view thereof;

FIG. 3 is an enlarged top plan view thereof;

FIG. 4 is an enlarged side elevational view thereof;

FIG. 5 is an enlarged right end view thereof; and,

FIG. 6 is an enlarged left end view thereof.

The broken line showing of a waist band and belt loops is for illustrative purposes only and forms no part of the claimed design.

The intersecting horizontal and vertical lines and the intersecting diagonal lines shown in FIGS. 1-3 represent stitching.
